UNITED STATES PATENT OFFICE

155,766

DESIGN FOR A GAME BOARD

Stanley E. Anderson and Gladys L. Menches,
Billings, Mont.

Application March 8, 1948, Serial No. 144,966

Term of patent 14 years

(Cl. D34—5)

To all whom it may concern:

Be it known that we, Stanley E. Anderson and Gladys L. Menches, citizens of the United States, residing at Billings, in the county of Yellowstone and State of Montana, have invented a new, original, and ornamental Design for a Game Board, of which the following is a specification, reference being had to the accompanying drawing, forming part thereof.

We claim:

The ornamental design for a game board, as shown.

STANLEY E. ANDERSON.
GLADYS L. MENCHES.
